(57) **ABSTRACT**

A gaming machine is described herein. The gaming machine includes a cabinet, a display device mounted to the cabinet, and a control unit operably coupled to the display device. The control unit includes a processor programmed to execute an algorithm to render an animated sequence of computer-generated images on the display device including the steps of rendering a denomination configuration screen on the display device including a plurality of selectable denominations and receiving an operator's selections of the selectable denominations including a first operator selected denomination and a second operator selected denomination. The processor determines an MDT multiplier based on the first operator selected denomination and determines an MDT denomination for each operator selected denomination based on the MDT multiplier.

20 Claims, 27 Drawing Sheets

Diagram illustrating the MDT Index and Multiplier values for different game denominations:

Game Denomination	MDT Denomination	MINOR Progressive Value	MINI Progressive Value
\$0.10	1	\$500	\$100
\$0.25	2.5	\$1,250	\$250
\$0.50	5	\$2,500	\$500
\$1.00	10	\$5,000	\$1,000

**GAMING MACHINE AND CONTROL
METHOD FOR OPERATING GAMING
MACHINES TO DISPLAY COMPUTER
ANIMATED REEL GAMES**

**CROSS-REFERENCE TO RELATED
APPLICATION**

This application claims the benefit of U.S. Provisional Patent Application Ser. No. 63/358,779, filed Jul. 6, 2022, the disclosure of which is hereby incorporated by reference in its entirety for all purposes.

TECHNICAL FIELD

The present invention relates to a gaming machine, a control method for a gaming machine, and a program for a gaming machine.

BACKGROUND ART

A gaming machine represented by a slot machine is highly popular among casino customers as a device that provides gaming that is easy to enjoy, and recent statistics report that sales from gaming machines account for the majority of casino earnings. Initial slot machines were simple devices, wherein an inserted coin is received, a configured reel rotates and stops mechanically according to a handle operation, and a win or a loss is determined by a combination of symbols stopped on a single pay line. However, recent gaming machines, such as mechanical slot machines driven by a highly accurate physical reel via a computer controlled stepping motor, video slot machines that display a virtual reel on a display connected to a computer, and various gaming machines that apply similar technology to other casino games are quickly advancing. For the manufacturers that develop these gaming machines, an important theme is to provide an attractive game that strongly attracts casino customers as players, and improves the functionality of the gaming machine.

SUMMARY OF THE INVENTION

In one aspect of the present invention, a gaming machine is provided. The gaming machine includes a cabinet, a display device mounted to the cabinet, and a control unit operably coupled to the display device. The control unit includes a processor programmed to execute an algorithm to render an animated sequence of computer-generated images on the display device including the steps of rendering a denomination configuration screen on the display device including a plurality of selectable denominations, receiving an operator's selection of the selectable denominations and determining an MDT multiplier based on an operator selected denomination, and determining an MDT denomination for each operator selected denomination based on the MDT multiplier. The processor initiates a reel game by rendering a game screen on the display device including a plurality of virtual reels, a selectable denomination icon indicating a current game denomination value and a progressive prize icon indicating a current progressive award value associated with the current game denomination value. The processor receives a player's selection of the selectable denomination icon and renders a game denomination selection screen on the game screen including a plurality of player selectable game denomination icons associated with game denomination values corresponding to each operator

selected denomination. The processor receives a player's selection of a player selectable game denomination icon indicating a selected game denomination value, determines a corresponding MDT denomination associated with the selected game denomination value, determines a corresponding progressive award value associated with the selected game denomination value based on the corresponding MDT denomination and a base progressive award value, and animates the progressive prize icon to transform the current progressive award value to the corresponding progressive award value associated with the selected game denomination.

In another aspect of the present invention, a method of operating a gaming machine is provided. The gaming machine includes a cabinet, a display device mounted to the cabinet, and a control unit including a processor operably coupled to the display device. The method includes the processor performing an algorithm to render an animated sequence of computer-generated images on the display device including the steps of rendering a denomination configuration screen on the display device including a plurality of selectable denominations, receiving an operator's selection of the selectable denominations and determining an MDT multiplier based on an operator selected denomination, and determining an MDT denomination for each operator selected denomination based on the MDT multiplier. The processor initiates a reel game by rendering a game screen on the display device including a plurality of virtual reels, a selectable denomination icon indicating a current game denomination value and a progressive prize icon indicating a current progressive award value associated with the current game denomination value. The processor receives a player's selection of the selectable denomination icon and renders a game denomination selection screen on the game screen including a plurality of player selectable game denomination icons associated with game denomination values corresponding to each operator selected denomination. The processor receives a player's selection of a player selectable game denomination icon indicating a selected game denomination value, determines a corresponding MDT denomination associated with the selected game denomination value, determines a corresponding progressive award value associated with the selected game denomination value based on the corresponding MDT denomination and a base progressive award value, and animates the progressive prize icon to transform the current progressive award value to the corresponding progressive award value associated with the selected game denomination.

In yet another aspect of the present invention, a non-transitory computer-readable storage media having computer-executable instructions embodied thereon to operate a gaming machine is provided. The gaming machine includes a cabinet, a display device mounted to the cabinet, and a control unit including a processor operably coupled to the display device. When executed by the processor, the computer-executable instructions cause the processor to perform an algorithm to render an animated sequence of computer-generated images on the display device including the steps of rendering a denomination configuration screen on the display device including a plurality of selectable denominations, receiving an operator's selection of the selectable denominations and determining an MDT multiplier based on an operator selected denomination, and determining an MDT denomination for each operator selected denomination based on the MDT multiplier. The processor initiates a reel game by rendering a game screen on the display device

including a plurality of virtual reels, a selectable denomination icon indicating a current game denomination value and a progressive prize icon indicating a current progressive award value associated with the current game denomination value. The processor receives a player's selection of the selectable denomination icon and renders a game denomination selection screen on the game screen including a plurality of player selectable game denomination icons associated with game denomination values corresponding to each operator selected denomination. The processor receives a player's selection of a player selectable game denomination icon indicating a selected game denomination value, determines a corresponding MDT denomination associated with the selected game denomination value, determines a corresponding progressive award value associated with the selected game denomination value based on the corresponding MDT denomination and a base progressive award value, and animates the progressive prize icon to transform the current progressive award value to the corresponding progressive award value associated with the selected game denomination.

BRIEF DESCRIPTION OF DRAWINGS

FIG. 1A is a perspective view of a gaming machine, according to an embodiment of the present invention.

FIGS. 1B-1G are perspective views of the gaming machine, according to other embodiments of the present invention.

FIG. 2 is a functional block diagram of the gaming machine in FIGS. 1A-1G.

FIG. 3 is an illustration of a game displayed on a display area of the gaming machine, according to an embodiment of the present invention.

FIG. 4 is an illustration of virtual reels that may be used with the game shown in FIG. 3, according to an embodiment of the present invention.

FIGS. 5-8 are block diagrams of a game control unit that may be used with to perform the function of executing a game on the gaming machine.

FIG. 9 is a functional block diagram of a server computer system, according to an embodiment of the present invention.

FIG. 10 is a front view of a mobile computing device that may be used with the server computer system of FIG. 9.

FIG. 11 is an illustration of exemplary reel strip data file for use in generating virtual reels shown in FIG. 4 and FIG. 16 with symbol arrangements showing the order of symbols displayed on the display area of the game, according to an embodiment of the present invention.

FIG. 12 is an illustration of a reel stop position data file that may be used to execute the game, according to an embodiment of the present invention.

FIG. 13 is an illustration showing one example of a pay line set on the determination area of the game.

FIGS. 14 and 15 are flow charts illustrating algorithms used during operation of the gaming machine and/or the mobile computing device to generate and render animated sequences of computer-generated images on graphic user interface screens to display the game to the player, according to one embodiment of the present invention.

FIGS. 16-19 are exemplary illustrations of animated sequences of computer-generated images of game screens illustrating the algorithms shown in FIGS. 14 and 15.

FIGS. 20-22 are illustrations of data files that may be used to execute the game, according to an embodiment of the present invention.

Corresponding reference characters indicate corresponding parts throughout the drawings.

DETAILED DESCRIPTION OF EMBODIMENTS

With reference to the drawings and in operation, the present invention is directed towards a gaming machine, a control method for a gaming machine, and a program for a gaming machine and/or mobile computing device that provides a game to a player. The gaming machine according to the present embodiment, receives a predetermined game value from the player, generates a game result, and provides a payout to the player according to the game result and one or more pay tables. The gaming machine includes a gaming cabinet that includes a display device and a user input device. The display device includes a display configured to display computer generated graphics. The user input device includes a plurality of input buttons that allows a player to initiate game play and interact with video images being displayed on the display device. The gaming machine includes a control unit having a computer processor that is programmed to generate and display a structured graphic user interface displayed on the display device using computer generated graphics. The structured graphic user interface includes a plurality of virtual reels displaying game symbols within a grid. The control unit is also programmed to animate the virtual reels to simulate spinning the virtual reels through the grid, and stop the virtual reels to reveal an outcome of a game. The control unit is also programmed to generate and render animated sequences of computer-generated images on graphic user interface screens to display bonus features associated with the game.

Referring to FIGS. 1A-1D, in the illustrated embodiment, the gaming machine 10 includes a cabinet 12 providing a display unit 14 and a control panel 16 and may also house a player tracking or ranking unit 18. The cabinet 12 also houses a game control unit 20 (see FIG. 2) that controls each part (see below). The control unit 20 also implements a random number generator (RNG) that is used during operation of the game. Each configuration is described below.

The display unit 14 may be liquid crystal display devices and/or organic EL display devices and the like, and by controlling via each control unit 20, the display area mentioned below functions as a display unit 14 provided to the player. In some embodiments, the display unit 14 may include an upper display 22 and a lower display 24. As shown in FIGS. 1A, 1F, and 1G, in some embodiments, the upper and lower displays 22, 24 are shown on a single display device. In other embodiments, as shown in FIGS. 1B-1E, the upper and lower displays 22, 24 may be shown on multiple display devices.

Speakers 26 are provided on the left and right of the cabinet 12, and by controlling via the control unit 20, sound is provided to the player. On the control panel 16, a bill/ticket identification device 28, a printer device 30, and an operation unit 32 are provided.

The player tracking unit 18 may be housed on the center of the front surface of the cabinet 12 below the display unit 14. The player tracking unit 18 has a card reader that recognizes a player identification card, a display that presents data to the player, and a keypad that receives input by the player. This type of player tracking unit 18 reads information recorded on the player identification card inserted by the player into the card reader, and displays the information and/or information acquired by communicating with the external system on the display, by cooperatively operating with the control unit 20 mentioned below or an

external system. Further, input from the player is received by the keypad, the display is changed according to the input, and communication with the external system is carried out as necessary.

The bill/ticket identification device 28 is disposed on the control panel 16 in a state where the insertion opening that a bill/ticket is inserted into is exposed, an identification part that identifies a bill/ticket by various sensors on the inside of the insertion opening is provided, and a bill/ticket storage part is provided on the outgoing side of the identification part. The bill/ticket identification device 28, receives and identifies bills/tickets (including vouchers and coupons) that are the game value as a game executing value, and notifies the control unit 20 mentioned below.

The printer device 30 is disposed on the control panel 16 in a state where the ticket output opening that a ticket is output from is exposed, a printing part that prints predetermined information on a printing paper on the inside of the ticket output opening is provided, and a housing part that houses the printing paper inside the paper inlet side of the printing part is provided. The printer device 30, under the control of the control unit 20 mentioned below, prints information on paper and outputs a ticket according to credit payout processing from the gaming machine 10. The output ticket can use the payout credit as game play by being inserted into the bill/ticket identification device 28 of another gaming machine, or, can be exchanged for cash by a kiosk terminal inside of the casino or a casino cage.

The operation unit 32 receives the operation of the player. The operation unit 32 includes a group of buttons 34 that receives various instructions from the player on the gaming machine 10. The operation unit 32, for example, may include a spin button and a group of setting buttons. The spin button receives an instruction to start (start rotating the reel) an instance of the game. The group of setting buttons 34 includes a group of bet buttons, a denomination button, a group of line-designation buttons, a max bet button, and a payout button and the like. The group of bet buttons receives an instruction operation regarding the bet amount of credits (bet number) from the player. The group of line-designation buttons receive an instruction operation that designate a pay line subjected to a line judgment below from the player. The max bet button receives an instruction operation regarding the bet of the maximum amount of credits that can be bet at one time from the player. The payout button receives an instruction operation instructing a credit payout accumulated in the gaming machine 10. The gaming machine 10 also includes illumination devices 36 that provides decorative lighting to the gaming machine 10.

In one embodiment, the control panel 16 includes a plurality of user input devices that may include an acceptor device which accepts media associated with a monetary value to establish a credit balance, a validator configured to identify the physical media, a cash-out button actuatable to cause an initiation of a payout associated with the credit balance. The acceptor device may include a touchscreen display associated with the display unit 14 and/or the player tracking unit 18, the bill/ticket identification device 28, the operation unit 32, the player tracking unit 18, a coin slot, a ticket in ticket out (TITO) system, a bill acceptor, and/or any suitable device that enables the gaming machine 10 to receive media associated with a monetary value and establish a credit balance for use in playing the gaming machine 10. In one embodiment, the acceptor device may be configured to receive physical media such as, for example, a coin, a medal, a ticket, a card, a bill, currency, and/or any suitable physical media that enables the gaming machine 10 to

function as described herein. The acceptor device may also be configured to accept virtual media such as, for example, a player tracking account, a virtual credit balance, reward points, gaming credits, bonus points, and/or any suitable virtual media that enables the gaming machine 10 to function as described herein.

For example, in one embodiment, the coin slot may include an opening that is configured to receive coins and/or tokens deposited by the player into the gaming machine 10. The control unit 20 converts a value of the coins and/or tokens to a corresponding amount of gaming credits that are used by the player to wager on games played on the gaming machine 10. The bill acceptor may include an input and output device that is configured to accept a bill, a ticket, and/or a cash card into the bill acceptor to enable an amount of gaming credits associated with a monetary value of the bills, ticket, and/or cash card to be credited to the gaming machine 10. In one embodiment, the bill acceptor also includes a printer (not shown) that is configured to dispense a printed voucher ticket that includes information indicative of an amount of credits and/or money paid out to the player by the gaming machine 10 during a gaming session. The voucher ticket may be used at other gaming devices, or redeemed for cash, and/or other items as part of a casino cashless system.

FIG. 2 shows a functional block diagram of the gaming machine 10, according to the present embodiment. The gaming machine 10 provides the control unit 20. Within the cabinet 12, control unit 20 includes a control board equipped with a central processing unit 38 (abbreviated as CPU below) including a processor, an interface unit (or part) 40, a memory device including a memory 42 and a storage 44, and the like are incorporated. The control board is configured so that communication is possible through the interface unit 40 and each of the components equipped on the cabinet 12. The CPU 38 controls the operation of each component by executing the program recorded in the memory 42 or the storage 44 of the CPU 38, and provides a game to the player. The function of the CPU 38 is to execute and display the game on the display unit 14 of the gaming machine 10.

The control unit 20 is configured as the interface unit 40 including a chip set providing communication functions of the CPU 38, a memory bus connected to a CPU 38, various expanding buses, serial interfaces, USB interfaces, Ethernet (registered trademark) interfaces and the like, and a computer unit where the CPU 38 provides the addressable memory 42 and the storage 44 through the interface unit 40. The memory 42 can be configured to include RAM that is a volatile storage medium, ROM that is a nonvolatile storage medium, and EEPROM that is a rewritable nonvolatile storage medium. The storage 44 provides the control unit 20 as an external storage device function, can use reading devices such as a memory card that is a removable storage medium, and a magneto optical disk and the like, and can use hard disks.

On the interface unit 40, in addition to the CPU 38, the memory 42, and the storage 44, a bill/ticket identification unit controller 46, a printer unit controller 48, the player tracking unit 18, a graphic controller 50, an input controller 52, and a sound controller 54 are connected. That is, the control unit 20 is connected to the operation unit 32 through the input controller 52, and connected to the display unit 14 through the graphic controller 50. Further, when illumination devices 36 that provides decorative lighting to the gaming machine 10 is provided, the illumination is controlled under the control of the control unit 20 on the interface unit 40, and an illumination controller 56 that

controls the illumination devices 36 to provide a decorative lighting effect may be connected.

The control unit 20, which includes memory 42 and storage 44, controls each part by executing a program stored in the memory 42 and the storage 44, and provides a game to the player. Here, for example, the memory 42 and storage 44 may be configured to store a program and data of an operating system and subsystem that provide the basic functions of the control unit 20 to the EEPROM of the memory 42, and stores a program and data of an application that provides a game to the storage 44. According to such a configuration, it can be easy to change or update a game by replacing the storage 44. Further, the control unit 20 may be a multiprocessor configuration that has a plurality of CPUs.

Each block connected to the control unit 20 is described below. The bill/ticket identification unit controller 46 operates the bill/ticket identification device 28 to receive bills/tickets in the insertion opening, and notifies the control unit 20 of identifying information corresponding to the assortment of bills or the payout processing of credits. The bill/ticket identification unit controller 46 notifies the information to the control unit 20, and the control unit increases the usable credit amount inside of the game according to the notified content. The printer unit controller 48 corresponds to the printer device 30, and under the control of the control unit 20 that receives an operation of the payout button of the group of setting buttons 34, information corresponding to the credit payout processing from the gaming machine 10 is printed and output on a printed ticket.

The player ranking (or tracking unit) unit 18 cooperatively operates with the control unit 20 and sends and receives information and the like of the player from the casino management system. The graphic controller 50 controls the display unit 14, under the control of the control unit 20, and displays a display image that includes various graphic data. The sound controller 54 drives the speakers 26 under the control of the control unit 20, and provides various sounds such as an announcement, sound effects, BGM and the like.

Further, the interface unit 40, has various communication interfaces for communicating with the exterior of the gaming machine 10, for example the interface unit 40 can communicate with an external network by Ethernet 58, 60, and a serial interface 62. In the present embodiment, one example shows when there is communication between a well-known server-side gaming network 58 (Server Based Gaming), a G2S network 60 (Game to System), and a slot information system 62 (Slot Data System), respectively.

FIG. 3 schematically shows a display area 64 provided by the gaming machine 10. Such a display area 64 is displayed on the display unit 14 (the upper display 22 and/or the lower display 24) by the control unit 20 executing a predetermined program. In the illustrated embodiment, the display area 64 is displayed on the lower display 24. For instance, as shown, during a game, the upper display 22 may be utilized to display game related information, e.g., game title information and/or graphics.

In one aspect of the present invention, the control unit 20 executes a game execution program to provide a game 66 that includes a computer-animated primary game 68 and one or more bonus feature events. The control unit 20 displays a game screen within the display area 64 that includes the primary game 68 and the bonus feature events. In the illustrated embodiment, the primary game 68 and the bonus feature events are displayed on the lower display 24. The upper display 22 may be used to display animations and/or game identifying information during the game and/or during

an attract mode. Further, the lower display 24 may display a decorative area, and an area that displays credit amount, bet number, and a credit amount obtained by winning (WIN number) and the like. In another embodiment, the primary game 68 may be displayed in the lower display 24 and the bonus feature events may be displayed in the upper display 22.

In the illustrated embodiment, the primary game 68 includes a video slot game using a plurality of virtual reels 70, 72, 74, 76, 78 (shown in FIGS. 3-4). The video slot game utilizes a grid 80 in the display area 64. The illustrated embodiment shows the state of displaying the display area 64 in the lower display 24. By using such a display area, the gaming machine 10 of the present embodiment operates as a slot machine that pays a payout according to a winning combination of symbols displayed on the display area 64.

The display unit 14 displays a plurality of game symbols in the grid 80. The grid 80 has a plurality of rows (r) and columns (c). The grid 80 is configured by a plurality of cells 82 that are the stop position of symbols. On each of the plurality of cells 82 of the display area 64, one symbol is stopped and displayed.

In the illustrated embodiment, the grid 80 is displayed with fifteen cells 82 arranged in three rows and five columns, and the control unit 20 generates five virtual reels 70, 72, 74, 76, 78 for use in displaying the primary game 68. On each cell 82 of the grid 80, as shown in FIG. 3, a game symbol 84 is displayed based on the symbol arrangement of virtual reels including virtual reels 70, 72, 74, 76, 78 (also shown in FIG. 4) configured as a virtual reel set 86. That is, the cells 82 of the grid 80 correspond to the virtual reels 70 to 78, by column, and the game symbols 84 disposed on predetermined parts of each virtual reels 70 to 78 are displayed. In the illustrated embodiment, each of the virtual reels 70 to 78 displays multiple symbols within a corresponding column with the virtual reel in a stopped position. For example, as shown in FIG. 3, when stopped, each virtual reel 70 to 78 displays game symbols within each corresponding column. Furthermore, by moving (scrolling or spinning) each game symbol 84 by column based on the symbol arrangement of the virtual reels 70 to 78, the game symbols 84 displayed in the cells 82 of the grid change, and by stopping the movement (scrolling or spinning) by columns, the game symbols 84 are stopped. Here, the virtual reels 70 to 78 are data where the control unit 20 uses a program having the memory 42 or the storage 44, and data showing the symbol arrangement (i.e., the order of symbols on each reel strip) regulated by each cell column. Further, the virtual reel set 86 is a general term for such virtual reels 70 to 78.

In some embodiments, the control unit 20 generates each virtual reel 70 to 78 using reel strip data files 88 (shown in FIG. 11) and symbol image data files stored in memory 42 and/or storage 44. The reel strip data file 88 includes a reel designation 90 associated with each virtual reel 70 to 78 and sequential symbol position logic cells 92 associated with each reel designation. Each symbol position logic cell 92 includes indicators for rendering the virtual reels with a plurality of game symbols. The reel strip data file 88 includes information associated with a plurality of reel strips 94, 96, 98, 100, 102 that correspond to each virtual reel 70 to 78, and are used to generate virtual reel 70 to 78. Each reel strip 94, 96, 98, 100, 102 includes a number of symbol positions 104 configured to be populated by game symbols 84 that are selected from symbol image data files stored in memory 42 and/or storage 44. The reel strips 94-102 also include reel stop positions 106 associated with each symbol position 104. The symbol positions 104 and the correspond-

ing game symbols **84** are arranged in an order defined by each reel strip **94, 96, 98, 100, 102**. In addition, one or more reel strips **94, 96, 98, 100, 102** includes a different number of symbol positions **104**.

In some embodiments, each reel strip **94, 96, 98, 100, 102**, includes a plurality of fixed symbol positions **104** for displaying game symbols **84**. Each fixed symbol position **104** includes instructions for displaying a predefined game symbol **84** selected from a set of game symbols **84** included in a game symbol image data file. For example, for each play of the game, the fixed symbol positions **104** have an associated predefined game symbol **84** from a symbol set. The game symbol image data file includes the details of game symbols **84** populating the fixed symbol positions **104** and includes varieties of game symbols **84**. This symbol set includes card symbols ("9", "10", "J", "Q", "K", and "A") that imitate playing cards as regular symbols, and picture symbols ("PicA", "PicB", "PicC", and "PicD") that show a pattern. Further, this symbol set includes a wild symbol ("Wild") that is substituted as another symbol when a win combination is determined and a special symbol ("Special") that may be used to determine if a game feature is to be provided. Each of these symbols have a different rank from each other regarding their value when winning, their rank gradually raises in this order: "9", "10", "J", "Q", "K", "A", "PicE", "PicD", "PicC", "PicB", "PicA". A combination of symbols that includes high-ranking symbols when winning, can obtain a larger winning payout compared to a combination of low-ranking symbols when winning.

One or more of the reel strips **94, 96, 98, 100, 102** may also include a plurality of variable symbol positions **104** that display a varying inner symbol ("inner"). The variable symbol positions **104** are populated using a variable symbol reel strip data file and/or a variable symbol weight table. The variable symbol reel strip data file includes a variable symbol reel strip that includes a number of symbol positions populated by game symbols that are selected from game symbol image files, and stop positions associated with each symbol position. When generating the virtual reels **70** to **78**, the control unit **20** is programmed to populate the variable symbol positions **104** by randomly selecting game symbols from the predefined group of symbols using the variable symbol reel strip. For example, the control unit **20** may be programmed to randomly select a stop position of the variable symbol reel strip, select the symbol position associated with the randomly selected stop position, and populate the variable symbol position **104** with the game symbol **84** associated with the selected symbol position.

It should be noted that in one aspect of the present invention, one or more dynamic virtual reel strips may be utilized. Using virtual reel strips, the symbols and/or symbol positions and/or virtual reel strips and/or length or size and/or any aspect of a virtual reel strip may change from one spin or play to the next. For example, a dynamic reel strip includes a plurality of symbol positions with symbols from the symbol set and a plurality of variable symbol positions. The variable symbol positions may be in the form of one or more stacks, i.e., adjacent symbol positions. In one embodiment, the location and/or size of the stacks may change from one spin to the next, either randomly and/or in a predetermined pattern.

Alternatively, a virtual reel strip associated with a column of cells may be dynamically changed from one spin or play to another spin or play. This, may occur randomly, every spin or play and/or in a predetermined pattern. It should be noted that in the illustrated embodiment, each column of the grid **80** has a corresponding reel. When the reel stops, a

symbol from the respective reel appears in each one of the cells of the respective column of the grid **80**.

In general, the control unit **20** starts an instance of the primary game **68** and determines the stop position of each virtual reels **70** to **78** randomly using a reel stop position data file **108** (shown in FIG. 12) stored in the memory device. The virtual reels **70** to **78** that are displayed in the display unit **14** (for example, the lower display **24**) are moved from a current position, and stopped based on a stop position to express an outcome of the primary game. Due to this, in the display or grid **80**, the symbols included on the virtual reels **70** to **78** are continuously moved (scrolled or spun) in a vertical direction of the display area **64**, and one symbol of one cell **82** is aligned in an order of the symbol based on the symbol arrangement is stopped so that it is displayed.

The control unit **20** changes and stops the plurality of symbols displayed on the display unit **14** according to the operation of the player received by the operation unit **32**, and a payout may be paid according to the stopped symbols inside the display area **64** and a pay line set and payable data file **110** (shown in FIG. 13) stored in the memory device.

In the display area **64**, a pay line is set that is used when winning is determined. The pay line is set to be extended over the column on the right end from the cells of the column of the left end, and is a line that combines the plurality of cells **82** determining a win. The number of effective lines within the set pay line is selected by the operation of a group of line designation buttons included in the group of setting buttons **34** of the operation unit **32** for the player. The control unit **20**, in regard to the result of a game that is a combination of symbols, determines a win when a predetermined number of identical symbols is surpassed and aligned on a set pay line, and pays a payout to the player according to the type and number of symbols. The system for determining a win may determine a win when a predetermined number of identical symbols from cells of the column on the left end are aligned on a set pay line, may determine a win when a predetermined number of identical symbols from cells of the column on the right end are aligned on a set pay line, and may determine a win when a predetermined number of identical symbols are aligned on a continuous column on a predetermined pay line. It should be noted that pay lines shown other than (or in addition to) the pay lines shown in FIG. 13 may be used. In general, the pay lines start in the first column and end in the last column, and include one cell per column. However, one or more pay lines could include one or more cells in the same column and may include a vertical pay line.

In some embodiments, upon detecting the occurrence of the trigger condition occurring with the primary game, the control unit **20** executes a bonus feature event algorithm to display a bonus feature event. For example, upon detecting the occurrence of the trigger condition, the control unit **20** may display additional game symbols and/or game animations on the game screen and/or transitions the game screen from the primary game to the bonus feature event.

Referring to FIGS. 5-8, in the illustrated embodiment, the memory **42** stores a game application program **200** that includes computer executable instructions that, when executed by the processor **38**, cause the processor **38** to generate and display the game on the display unit **14** of the gaming machine **10**. In one embodiment, the game application program **200** includes program code **202** and program object data **204** that includes computer executable instructions for implementing a game using the algorithms shown in FIG. 14.

11

In the illustrated embodiment, the memory 42 stores the game application program 200 and a system application program 206 that includes computer executable instructions that, when executed by the processor 38, cause the processor 38 to generate and display the game on the display unit 14 of the gaming machine 10. The game application program 200 provides game specific/front-end functions and the system application program 206 program provides generic/back-end functions, when executed by the processor 38. In the illustrated embodiment, the game application program 200 and the system application program 206 are implemented on the same operating system. However, it should be noted that these programs may be implemented on different operating system and/or by different processors. In one embodiment, the game application program 200 includes a plurality of software modules including a bet/denomination/payline button listener module 208, a start button listener module 210, a credit balance manager module 212, a sampling manager 214, a random number generator 216, a comparison manager 218, a game result generator 220, a win evaluator 222, a game presenter 224, a game graphics presenter 226, a game sound presenter 228, a win indicator 230, an award provider 232, an application manager 234, and an external communicator 236. The game application program 200 may also include the reel strip data files, the symbol image data files, the variable symbol reel strip data files, the reel stop position data file, the credit prize symbol weight tables, the pay line set, and the payable data file.

The bet/denomination/payline button listener module 208 is a software module for receiving a signal from the bet button, the denomination button, or the payline button which is generated by the button when a player operates the button to select number of bet, denomination, or number of paylines. In response to receiving the signal, the bet/denomination/payline button listener module 208 communicates the occurrence of the signal to application manager 234 for changing bet, denomination, or payline configuration of the game.

The start button listener module 210 is a software module for receiving a signal from the start button which is generated by the button when a player operates the button to start a game. In response to receiving the signal, the start button listener module 210 communicates the occurrence of the signal to application manager 234 for starting the game.

In response to receiving the signal from start button listener module 210, the application manager 234 requests the sampling manager 214 to obtain necessary number of random numbers from the random number generator 216.

The random number generator 216 generates random numbers based on predetermined algorithm of computational random generation method. The random number generator 216 may be a pseudorandom generator. In response to a request from sampling manager 214, the random number generator 216 returns random number. In some implementations, the random number generator 216 may be implemented in a central server. The random number generator 216 may be implemented as an integrated circuit or hard wired logic.

The comparison manager 218 compares the current state of the game or each random number with the reel strip data files, the symbol selection data files, the reel stop position data file, the pay line set, and/or the payable data file and specifies corresponding reel layout, stop position, prize symbol, or trigger symbol based on each random number.

The game result generator 220 generates game result based on selected reel layout, stop positions of each reel, and bonus features.

12

The win evaluator 222 evaluates the game result with reference to the pay table.

The game presenter 224 provides game presentation process with visual and sound so as to form the predetermined game result finally.

The game graphics presenter 226 provides visual game presentation process on the display so as to form the predetermined game result finally.

The game sound presenter 228 provides sound presentation process by using sound controller and speakers.

The win indicator 230 indicates win combinations and payment condition of prize symbol formed in the game result.

The award provider 232 provides award credit to win meter based on the win evaluation.

The application manager 234 administers activity and status of each software module. In addition, the application manager 234 administers configuration, progress and states of the game application program 200.

The external communicator 236 communicates instruction and data with the system application program 206.

The credit balance manager module 212 executes a process for decrementing credit balance and incrementing credit balance based on win amount displayed in win meter.

In the illustrated embodiment, the system application program 206 provides back ground processing and functions other than game specific functions. The system application program 206 includes a plurality of software modules including a system manager 238, a security manager 240, a slot management module 242, a denomination manager 244, a data logger 246, a communications manager 248, a bill acceptor manager 250, a metering module 252, and a cashout manager 254.

The system application program 206 may also include a game recall file 256, accounting logs 258, and meters 260.

The system manager 238 is a software module for administering all of the back ground processing and functions other than game specific functions conducted by the system application program 206.

The security manager 240 is a software module for administrating game verification, door security and monitoring security sensors.

The slot management module 242 is a software module for administrating data accumulation and communicating with external slot information system 62.

The denomination manager 244 is a software module for establishing denomination setting of the gaming machine 10. The denomination setting may include 1 cent, 2 cent, 5 cent, 25 cent, 1 dollar, 5 dollar and the like.

The data logger 246 is a software module for logging result of each primary game and the free game bonus to the game recall. In addition, the data logger 246 stores error events, bill log, cashout log, ticket log etc. to the accounting log.

The game recall file 256 is an accumulated data including results of each primary game and free game bonus. The game recall file 256 is stored in a non-volatile memory.

The accounting logs 258 is an accumulated data including error events, bill log, cashout log, ticket log etc. The accounting logs 258 are stored in a non-volatile memory.

The communications manager 248 is a software module for administrating communication between game application program 200 and system application program 206. The communications manager 248 also administers network communication between system application program 206 and external network such as slot management system

network, G2S network, gaming server for server based gaming network or VLT system network.

The bill acceptor manager 250 is a software module for administrating the bill acceptor and receives bill information inserted in the bill acceptor. In response to receiving the information from the bill acceptor, the bill acceptor manager 250 communicates with the metering for incrementing credit balance based on the inserted bill.

The metering module 252 is a software module for adjusting values of the meters 260 in response to communication with the game application program 200 via communications manager 248, the bill acceptor manager 250 or the cashout manager 254. The meters 260 includes a credit meter for indicating current credit balance on the gaming machine and a win meter for indicating win amount of current game session. The meters further include back ground meters such as coin-in, coin-out, total drop, attendant paid jackpots and/or bill-in. These meters might be implemented as data on the non-volatile memory or hardware meters.

The cashout manager 254 is a software module for administrating cashout procedure. In response to a player's operation on the cashout button, the cashout manager 254 is activated and the gaming machine pay total amount of the credit meter.

Referring to FIGS. 9 and 10, in one embodiment, the present invention includes a networked server computer system 300 that is configured to deliver the game to one or more client computing devices 302 over the Internet. In the illustrated embodiment, the networked computer system 300 includes an iGaming server system 304 that is coupled in communication with one or more client computing devices 302 via a communications network 306. The communications network 306 may be any suitable connection, including the Internet, an Intranet, LAN, a virtual private network (VPN), cellular networks, etc. . . . , and may utilize any suitable or combination of technologies including, but not limited to wired and wireless connections, always on connections, connections made periodically, and connections made as needed.

The client computing device 302 may include any suitable device that enables a user to access and communicate with the server system 300 including sending and/or receiving information to and from the server system 300 and displaying information received from the server system 300 to a user. In the illustrated embodiment, the client computing device 302 includes a processor coupled to a memory device. The memory device stores various programs and data that are executed by the processor for operating the client computing device 302. The client computing device 302 also includes an input device configured to receive operational inputs from the user, and a display device configured to display a graphical user interface. The input device and display device enable a user to interact with the server system 300 via the client computing device 302. For example, in one embodiment, the client computing device 302 may include, but is not limited to, a desktop computer, a laptop or notebook computer, a tablet computer, smartphone/tablet computer hybrid, a personal data assistant, a handheld mobile device including a cellular telephone, and the like. In one embodiment, the processor of the client computing device 302 may be programmed to function as the control unit 22 of the gaming machine 10.

In the illustrated embodiment, the client computing device may include a web browser program stored in the memory device. The processor executes the web browser program to display web pages on the display device that

includes information received from the server system 300 to enable a user to interact with and operate the server system 300.

In one embodiment, the client computing device 302 includes a mobile computing device 308 (shown in FIG. 10) such as, for example, a tablet computer, a smartphone/tablet computer hybrid, a smartphone such as an iPhone™, and the like. The mobile computing device 308 includes a processor coupled to a memory device for storing various programs and data for use in operating the mobile computing device 308. The mobile computing device 308 may also include a display unit 14 including a touchscreen, one or more video image cameras, one or more speakers, a microphone, at least one input button, and one or more sensors including, but not limited to, a touch ID fingerprint sensor coupled to an input button, a barometer, a three-axis gyro, an accelerometer, proximity sensor, and an ambient light sensor. In addition, the mobile computing device 308 may also include a Wi-Fi antenna, a cellular network antenna, a Bluetooth™ communications device, assisted GPS and GLONASS, a digital compass, and an iBeacon™ microlocation device.

The mobile computing device 308 may be programmed to store and execute mobile computer program applications that display graphical user interfaces on the touchscreen display unit 14 including display area 64 that allows the user to access the server system 300 to retrieve and store information within the server system 300 as well as interact with and operate the server system 300. In addition, in one embodiment, the server system 300 may install one or more mobile computer application programs in the memory device of the mobile computing device 308. When initiated by the processor of the mobile computing device 308, the mobile computer application program causes the processor of the mobile computing device 308 to perform some or all of the functions of the gaming machine 10.

In the illustrated embodiment, the server system 300 includes one or more remote gaming servers 310, one or more back-end servers 312, one or more real money gaming website hosting servers 314, and one or more social gaming website hosting servers 316. In the illustrated embodiment, the social gaming website hosting server 316 and the real money gaming website hosting server 314 are programmed to host a website that is accessible by a user via one or more client computing devices 302. The website hosting servers 314 and 316 execute a website application program that retrieves application code from the back-end server 312 and executes the application code to render one or more webpages on a display device of a client computing device 302 in response to requests received from the user via the client computing device 302 to allow users to interact with the website. The website hosting servers 314 and 316 are configured to generate and display webpages displaying a game. For example, the real money gaming website hosting server 314 is configured to host a real money wagering website that enables players to convert monetary funds to gaming credits that may be used to place wagers on the game. The social gaming website hosting server 316 is configured to host a social media and/or social gaming website that allows players to receive gaming credits for activities such as purchasing goods and/or services through an e-commerce website, and/or purchase gaming credits that may be used to play the game.

Each back-end server 312 is configured to perform operations to support the functions of the webpages and/or website being displayed by the website hosting servers 314 and 316. For example, in one embodiment, the back-end servers 312 may include a player account system server that

is configured to generate player accounts that include data associated with a player including, but not limited to, player identification information, player financial account information, player gaming credit account information, and/or any suitable player information, that may be used to establish credit meters and allow players to place wagers on the game.

Each remote gaming server 310 includes one or more copies of the game application program 200 stored in a memory device of the remote gaming server 310. A processor of the remote gaming server 310 is programmed to retrieve and transmit the game application program 200 to one or more back-end servers 312 for use in displaying the game to the user via a webpage being displayed by the web browser program.

In one embodiment, the game application program 200 may include instructions for rendering the game and executing the game on the client computing device 302. For example, the game application program 200 may include instructions for generating rendered code, such as, for example HTML code, which may be used by the web browser program of the client computing device 302 for displaying the game. For example, the game application program 200 may include program software code including, but not limited to, HTML, JavaScript, cascade style sheets (CSS), and any suitable programming code that may be used for rendering and operating the game via a website and/or mobile computer application.

In one embodiment, upon receiving a request from the website hosting servers 314, 316 via the back-end server 312, the remote gaming server 310 may execute the game application program 200 to operate the game, and execute a render-to-string operation to generate rendered code indicative of the game, such as, for example HTML code, and transmit the rendered code to the back-end server 312. The back-end server 312 may then transmit the rendered code to the corresponding website hosting servers 314, 316 for use in displaying the game on the website. As the player plays the game, the remote gaming server 310 may execute the game application program 200 for each instance of the game, and transmit rendered code to the back-end servers 312.

In another embodiment, the remote gaming server 310 may transmit the game application program 200 to the back-end server 312 and/or the website hosting servers 314, 316. The back-end server 312 and/or the website hosting servers 314, 316 may then execute the game application program 200 to initiate the instances of the game and execute render-to-string operations to generate rendered code indicative of the game.

In yet another embodiment, the back-end server 312 may receive a request to initiate the game from a mobile computing device 308 executing the mobile computer application program. Upon receiving the request, the back-end server 312 may access the game application program 200 and execute a render-to-string operation to generate rendered code indicative of the game and transmit the rendered code to the mobile computing device 308. In one embodiment, the back-end server 312 may continuously execute the game application program 200 to generate each instance of the game using a random number generator of the back-end server 312 based on input received from the mobile computing device 308 and generate and transmit rendered code for each instance of the game to the mobile computing device 308. In another embodiment, the back-end server 312 may execute a partial-render operation and generate partially-rendered code of the game using the game application program 200, and transmit the partially rendered code of the game and object data of game assets to the mobile comput-

ing device 308. The partially rendered code includes instructions for generating rendered code using the game assets and a random number generator of the mobile computing device for generating and displaying the game on the mobile computing device 308 using the mobile computer application program.

In one embodiment, the game application program 200 may be stored on several different servers. The game code on these servers is used to distribute game content to social or real money gaming websites and mobile applications. The distribution method is very flexible. For example, the game code and/or game application program 200 including game code and game object assets may be stored on a remote gaming server 310. One remote gaming server 310 may be connected to one or more back-end server 312.

Each back-end server 312 is configured to distribute the games to one or more websites or mobile applications. Players connect to these websites/mobile applications with the client devices or mobile devices and have access to the game content. A copy of game application program 200 including game code and game object assets is stored on the remote gaming server 310 for each back-end server 312 that is connected to the remote gaming server 310 and that distributes the game. For example, if one remote gaming server 310 is connected to two back-end servers 312, which is connected to three website hosting servers 314, 316 that distribute the game, the remote gaming server 310 would store two copies of the game application program 200 including game code and game object assets for the game (e.g., one copy for each back-end server 312).

For example, the server system 300 may be configured to implement the game on a mobile application such as, for example, "my KONAMI Slots™" mobile application available in Apple iOS™, Google Android™, and Amazon Kindle™ operating platforms, or on social-media websites such as the "my KONAMI Slots™" available on Facebook™. In one embodiment, the mobile application may download the game code from remote gaming server 310 via the real money gaming site 314 or the social gaming site 316 and execute the game code on the client computing device 302. In this embodiment, the game code may provide game specific/front-end function when executed by the processor of the client computing device, and the back end system 312 may provide generic/back-end function.

FIGS. 14 and 15 are flow charts of methods 400 and 500 illustrating the algorithms included in the game application program 200 and performed by the processor 38 when executing the game application program 200 for operating the gaming machine 10 and/or iGaming server system 300 to generate and render animated sequences of computer-generated images on graphic user interface screens to display the game to the player. The methods include a plurality of steps. Each method step may be performed independently of, or in combination with, other method steps. Portions of the methods may be performed by any one of, or any combination of, the components of the gaming machine 10 and/or iGaming server system 300.

For example, the game application program 200 may include computer-executable instructions including algorithms for providing the *Mystical Pearl™* slot games offered by Konami Gaming™ Inc.

In the illustrated embodiment, the game application program 200 includes computer instructions for generating the primary game 68 and the bonus feature event. In general, the bonus feature event is executed when a triggering event is detected during the primary game 68. In one embodiment, the primary game 68 includes a reel-type game that includes

a plurality of virtual reels that spin and stop to display the outcomes of the primary game. In other embodiments, the primary game **68** may include a playing card game, a bingo game, a Keno game, and/or any suitable casino type wagering game.

In the illustrated embodiment, the control unit **20** is programmed to execute the algorithm illustrated in method **400** for executing the game and rendering animated sequences of computer-generated images shown in FIGS. **3** and **16-21** displaying the game on the display unit **14**. In method step **402**, the processor **38** of the control unit **20** generates the virtual reels **70-78** for use with an instance of the primary game **68**, and displays the virtual reels **70-78** in the grid **80**.

In method step **404**, the processor **38** receives a signal to initiate an instance of the game **66** and generates the virtual reels **70-78** for use during the instance of the game **66**. For example, the processor **38** may receive a signal from the display unit **14** and/or the operation unit **32** indicating a player's request to initiate an instance or play of the game **66**. In one embodiment, the player may transmit a request to initiate an instance or play of game **66** by depressing a corresponding "spin" button on the operation unit **32** by touching a corresponding button icon being displayed on a touchscreen of the display unit **14**. Upon receiving a signal from the display unit **14** and/or the operation unit **32**, the processor **38** initiates the instance of the game **66** by generating the virtual reels **70-78** for use in the primary game **68**.

In method steps **406-416**, the processor **38** randomly determines an outcome of an instance of the primary game **68** and spins the virtual reels **70** to **78** and sequentially stops the virtual reels **70** to **78** to display the randomly generated outcome including a game symbol being displayed in each cell **82** of the grid **80**. For example, in one embodiment, the processor **38** starts spinning each virtual reel **70** to **78**, obtains random numbers from the random number generator, and determines a stop position of each virtual reel **70** to **78** based on the random numbers and the reel stop position data file **108**. In the illustrated embodiment the reel stop position data file **108** includes a range of random numbers associated with each symbol position in the sequence of symbol positions associated with the virtual reel. In one embodiment, the processor may obtain a random number for each simulate virtual reel **70** to **78**, i.e., five random numbers. The processor **38** then establishes a reel stop counter, "i", and sets the reel stop counter, i, equal to 1. The processor **38** then identifies the *i*th virtual reel strip associated with the stop counter, i, and stops the identified virtual reel strip to display the corresponding symbols in the corresponding cells **82** associated with the identified virtual reel strip. The processor **38** then increments the reel stop counter, i, by 1, i.e., *i*=*i*+1, and repeats the process of identifying the virtual reel strip associated with the incremented reel stop counter and stopping the identified virtual reel. This process continues until each virtual reel has been stopped. In this embodiment, for example, the virtual reels are numbered **1-5**. In one embodiment, during the reel spin, the player may initiate the stopping of the reels by depressing the spin button, which enables the player to accelerate game play.

In method step **418**, the processor **38** determines whether a trigger condition has been detected in the outcome of the primary game **68**. If a trigger condition is detected during the primary game **68**, the processor **38** initiates the bonus feature event in method step **420**.

In method step **422**, upon completion of the primary game **68** and/or the bonus feature event, the processor **38** deter-

mines and provides any award associated with the outcome of the primary game **68** and/or the bonus feature event. For example, the processor **38** may determine whether any winning combination of symbols is displayed in the outcome of the instance of the primary game **68** and/or the bonus feature event provide an award by increasing a balance of the credit meter based on the amount of the award.

In some embodiments, the control unit **20** is programmed to execute the algorithm illustrated in method **500** for executing the game and rendering animated sequences of computer-generated images shown in FIGS. **16-21** displaying a computer-animated primary reel game **68** (shown in FIGS. **3**, and **16-19**).

In the illustrated embodiment, the processor **38** executes a progressive game implementation that includes a Multi-denomination tokenization (MDT) standardized system by which progressive values may (or may not) scale by denominational settings. The MDT System enables an easy switching of denominations by a player while maintaining a working and correctly scaling progressive/jackpot game.

The MDT System essentially performs 3 supertasks when installed into a game: 1) Limiting the configurability of the game in the RAM Clear; 2) Enabling the easy scaling of jackpot values during gameplay based on a player changing the Denom settings; and 3) Checking and disabling or enabling the game based on settings that may be invalid.

The MDT system includes 3 Core Concepts: the MDT Denomination, the MDT Multiplier, and the MDT Index. The MDT index is a 0 based value supplied by the platform which controls the lowest available denom that the operator may set up in the RAM Clear. This may be accessed through the common game options by looking for:

CGMOPT_MIN_BASE_DENOM

If this value is not supplied by the platform, it will default to 0, and enable all denominations for selection by the operator. If this value is greater than 0, it will disable available denoms starting from the lowest possible denomination (based on country settings). In the US jurisdiction, if the MDT index value is set to 2, it will disable denominations \$0.01 and \$0.02 from being selected. For example, in FIG. **17**, a MDT Min Denom value of 1 has disabled the 1 Cent (\$0.01) Denom.

The MDT Multiplier: The MDT Multiplier always reflects the first enable denomination. This may be accessed by way of:

DenomInformation::GetMDTMultiplier; Or
GameApplication::GetMDTMult

For example, assume the operator enabled denoms 2, 5, and 10. The MDT multiplier will always be 2 upon starting the game. This is typically used to multiply Progressive Values, but this may be modified.

The MDT Denomination: The MDT Denom is a separate denom value that runs independent of any other type of denom in the game. This may be accessed by way of:

55 GameApplication::GetMDTDenom; and
DenomInformation::GetMDTDenom

The MDT Denom is essentially a denom value that switches with the player denom selection which may be used to reference data about itself. This may be used to scale progressive values, trigger values, etc. Based on what the operator of the EGM set as their first enable denomination in the payable setup, that denomination, whatever it may be, will always reflect to a MDT Denom value of 1. If multiple denominations are selected, this MDT Denom value will scale based on the first enabled denomination.

For example, assume that the Operator enabled the denoms 2, 5, and 10. The first denom will refer to an MDT

Denom of value of 1. If the user selects a denom of 5, divide this by the first enabled denom. $5/2=2.5$, The MDT Denom will become 2.5. If the user selects a denom of 10, divide this by the first enabled denom. $10/2=5$, the MDT Denom will become 5

The processor 38 also provides a base currency flag to denote which denom is the base accounting denom and a minimum denomination multiplier. The min denom multiplier will be used to scale the jackpot amounts of the \$0.01 USD (or other min USD denom) math based on the min denom selected by the operator. This will scale the progressives by a factor and maintain the RTP of the USD math without modifying the underlying probabilities making the game play the same as in the USD markets. This model should work for all 3 of the current major types of progressive games: Mystery triggered—random chance per spin, across bets/denoms, single denom, etc.; Scaled progressives by denom—Denom Reset amounts scale based on active denom and are not linked to each other across denom; and Linked progressives by denom—Denom Reset amounts do not scale based on active denom and odds will scale based on bet/denom played.

The processor 38 also would filters out which denoms the game supports for that market based on if there exists a “virtual denom” in the game based on the (Currency Denom/ Denom Multiplier)—Virtual Denom. For example, as shown in FIG. 22, the US math included Virtual Denoms for 0.025 and 0.04, but only the 0.04 was used for this particular currency. All progressive resets would be multiplied by 5. In the US, the denoms for 0.025 and 0.04 do not exist in the USGMD and would not be selectable. This approach allows the operator to update the min denom and update the game’s progressive resets as well. This will allow the same game to use a new platform and work for the devalued currency. Math can provide additional models with different progressive seeds and these can be configured by the operator in a drop down.

Given this approach, math would need to provide additional math for these Virtual Denoms for progressive games. This should be minimal work on games utilizing weighted tables to trigger progressives, but can be more costly for line, ways, or other types of non-weighted table triggered progressives. The full Virtual Denom list that math would need to support for all denoms in all markets is: 0.01, 0.0125, 0.02, 0.025, 0.04, 0.05, 0.08, 0.10, 0.125, 0.2, 0.25, 0.40, 0.50, 0.80, 1.00, 1.25, 2.00, 2.50, 5.00. FIG. 20 illustrates the current denoms for International which are configurable by the operator.

In the illustrated embodiment, the processor 38 executes method 500 to execute the MDT standardization system. For example, in method step 502, the processor 38 renders a denomination configuration screen 120 on the display device 14 that includes a plurality of selectable denominations 122. Each selectable denomination 122 includes a corresponding denomination value 124 and a plurality of return to player (RTP) values 126 and/or payback percentage values that may be used to determine a paytables and/or winning outcomes associated with the game 68.

In method step 504 the processor 38 receives an MDT index value 128 (shown in FIG. 21) from an operator via the denomination configuration screen 120 and enables corresponding selectable denomination 122 to be selectable by the operator. For example, in some embodiments, the processor 38 may render the denomination configuration screen 120 to include a plurality of enabled denominations 130 and a plurality of disabled denominations 132. The plurality of enabled denominations 130 are selectable by the operator

and the plurality of disabled denominations 132 are not selectable by the operator. In some embodiments, for example, each selectable denomination 122 displayed on the denomination configuration screen 120 is associated with a ranked numerical index value selected from a range of values, e.g. 0-8, indicating the ranked order of denominations from lowest denomination value to highest denomination value. For example, as shown in FIG. 17, the denomination configuration screen 120 displays nine selectable denominations 122 having denomination values including \$0.01, \$0.02, \$0.05, \$0.10, \$0.25, \$0.50, \$1.00, \$2.00, and \$5.00. Each selectable denomination 122 is associated with a ranked numerical index value based on the corresponding denomination value. For example, denomination value \$0.01 is assigned an index value of 0, denomination value \$0.02 is assigned an index value of 1, denomination value \$0.05 is assigned an index value of 2, denomination value \$0.10 is assigned an index value of 3, denomination value \$0.25 is assigned an index value of 4, denomination value \$0.50 is assigned an index value of 5, denomination value \$1.00 is assigned an index value of 6, denomination value \$2.00 is assigned an index value of 7, and denomination value \$5.00 is assigned an index value of 8. The MDT index value is a numerical index value selected from the range of values 0-8.

The processor 38 receives an MDT index value from the operator and transforms a number of enabled denominations 130 displayed on the denomination configuration screen 120 to disabled denominations 132 based on the received MDT index value. In some embodiments, the MDT index value indicates a desired lowest available denomination. The processor 38 may receive the MDT index value from the operator indicating a desired lowest available denomination, determine a denomination value associated with the MDT index value, and transform current enabled denominations 130 having corresponding denomination values lower than the desired lowest available denomination to disabled denominations 132 being displayed on the denomination configuration screen 120. For example, upon receiving an MDT index value equal to 2 from the operator, the processor 38 identifies denomination value \$0.05 having an assigned index value matching the received MDT index value, and transforms the denomination value \$0.01 and the denomination value \$0.02 from enabled denominations 130 to disabled denominations 132 as having assigned index values that are less than the received MDT index value. In some embodiments, the processor 38 may display disabled denominations 132 in a partially opaque obscured or greyed-out format to indicate to the operator that the disabled denominations 132 are not selectable from the denomination configuration screen 120. The processor 38 may also display enabled denominations 130 in a highlighted format, e.g. displayed with a brightened frame, to indicate to the operator that the enabled denominations 130 are selectable from the denomination configuration screen 120.

In some embodiments, the processor 38 may render a currency selection screen 134 on the display device 14 that includes a plurality of denomination values 124 associated with a plurality of currencies 136 corresponding to different geographic jurisdictions and/or countries. The processor 38 may receive an operator’s selection of a country currency 136 and populate the denomination configuration screen 120 to include the denomination values 124 associated with the selected currency 136.

In method step 506, the processor 38 receives an operator’s selections of the selectable denominations 122, determines an MDT multiplier 138 (shown in FIG. 21), and

determines an MDT denomination **140** for each operator selected denomination **124** based on the MDT multiplier. For example, the processor **38** receives an operator's selections of the selectable denominations and determines the MDT multiplier based on an operator selected denomination. For example, the processor **38** may determine the MDT multiplier equal to an operator selected denomination having a lowest denomination value of the operator selected denominations. In some embodiments, the processor **38** may receive the MDT index value from the operator and determine the MDT multiplier based on the enabled denomination having the lowest denomination value. For example, upon receiving an MDT index value equal to 3 from the operator, the processor **38** identifies the denomination value \$0.10 having an assigned index value matching the received MDT index value of 3 and determines the MDT multiplier to be equal to \$0.10, matching the identified denomination value \$0.10 having an assigned index value matching the received MDT index value of 3.

In the illustrated embodiment, the processor **38** determines an MDT denomination for each operator selected denomination based on the MDT multiplier. The processor **38** may determine each MDT denomination by dividing a corresponding operator selected denomination by the MDT multiplier. For example, in one embodiment, as shown in FIG. 21 the processor **38** may generate a denomination data file **142** including MDT denominations for each operator selected denomination based on the MDT multiplier. In this example, the operator has selected an MDT index value of 3, and selected denomination values of \$0.10, \$0.25, \$0.50, and \$1.00 via the denomination configuration screen **120**. The processor **38** identifies the denomination value \$0.10 having an assigned index value matching the received MDT index value of 3 and determines the MDT multiplier to be equal to \$0.10. The processor **38** then determines an MDT denomination **140** for each selected denomination value by dividing each denomination value by the MDT multiplier. For example, the processor **38** determines the MDT denomination associated with the denomination value \$0.10 to be 1 (i.e., denomination value/MDT multiplier=MDT denomination; \$0.10/\$0.10=1). The processor **38** also determines the MDT denomination associated with the denomination value \$0.25 to be 1 (i.e., \$0.25/\$0.10=2.5); determines the MDT denomination associated with the denomination value \$0.50 to be 5 (i.e., \$0.50/\$0.10=5); and determines the MDT denomination associated with the denomination value \$1.00 to be 10 (i.e., \$1.00/\$0.10=10).

In method step **508**, the processor **38** initiates the computer-animated reel game **68** by rendering a computer-animated game screen **142** on the display device **14** including a plurality of virtual reels **70, 72, 74, 76, 78**, a selectable denomination icon **144** indicating a current game denomination value and a progressive prize icon **146, 148** indicating a current progressive award value associated with the current game denomination value. As shown in FIG. 16 the processor **38** may display the game screen including a MINOR progressive prize icon **146** indicating a first scalable progressive award and a MINI progressive prize icon **148** indicating a second scalable progressive award.

In method step **510**, the processor **38** receives a player's selection of the selectable denomination icon **144** and renders a game denomination selection screen **150** (shown in FIGS. 18-19) on the game screen **142** including a plurality of player selectable game denomination icons **152** associated with game denomination values corresponding to each operator selected denomination. As shown in FIG. 18, in this example, the processor **38** renders the game denomination

selection screen **150** including player selectable game denomination icons **152** associated with denomination values of \$0.10, \$0.25, \$0.50, and \$1.00, which correspond to the operator selected denomination values of \$0.10, \$0.25, \$0.50, and \$1.00 selected via the denomination configuration screen **120**.

In method step **512**, the processor **38** receives a player's selection of a player selectable game denomination icon **152** via the game denomination selection screen **150** indicating a selected game denomination value and determines a corresponding MDT denomination **140** associated with the selected game denomination value. For example, in one embodiment, upon receiving a player's selection of a player selectable game denomination icon **152** via the game denomination selection screen **150**, the processor **38** may access the denomination data file **142** and select the MDT denomination matching the player selected game denomination value. In some embodiments, as shown in FIG. 18, the processor **38** may highlight the player selected game denomination value on the game denomination selection screen **150** to indicate the player's selection.

In method step **514**, the processor **38** determines a corresponding progressive award value associated with the selected game denomination value based on the corresponding MDT denomination and a base progressive award value, and animates the progressive prize icon **146, 148** to transform the current progressive award value to the corresponding progressive award value associated with the selected game denomination. For example, in some embodiments, the processor **38** may determine the corresponding progressive award value associated with the selected game denomination value by multiplying the base progressive award value by the corresponding MDT denomination associated with the selected game denomination value. The base progressive award value may be set as the progressive award value associated with the lowest game denomination. For example, as shown in FIG. 21, the processor **38** may generate the denomination data file **142** including a base MINOR progressive award value equal to \$500, and determine each corresponding MINOR progressive award value associated with each game denomination value by multiplying the base MINOR progressive award value by the corresponding MDT denomination. In this example, the processor **38** determines the MINOR progressive award value associated with the denomination value \$0.10 to be equal to \$500 (i.e., base progressive award value×MDT denomination=corresponding progressive award value; \$500×1=\$500). The processor **38** also determines the MINOR progressive award value associated with the denomination value \$0.25 to be equal to \$1,250 (i.e., \$500×2.5=\$1,250); determines the MINOR progressive award value associated with the denomination value \$0.50 to be equal to \$2,500 (i.e., \$500×5=\$2,500); and determines the MINOR progressive award value associated with the denomination value \$1.00 to be equal to \$5,000 (i.e., \$500×10=\$500).

The processor **38** may also generate the denomination data file **142** including a base MINI progressive award value equal to \$100, and determine each corresponding MINI progressive award value associated with each game denomination value by multiplying the base MINI progressive award value by the corresponding MDT denomination. In this example, the processor **38** determines the MINI progressive award value associated with the denomination value \$0.10 to be equal to \$100 (i.e., \$100×1=\$100); determines the MINI progressive award value associated with the denomination value \$0.25 to be equal to \$250 (i.e., \$100×

2.5=\$250); determines the MINI progressive award value associated with the denomination value \$0.50 to be equal to \$500 (i.e., \$100×5=\$500); and determines the MINI progressive award value associated with the denomination value \$1.00 to be equal to \$1,000 (i.e., \$100×10=\$1,000).

As shown in FIG. 19, the processor 38 may display the game screen 142 including a game denomination equal to \$1.00, the MINOR progressive prize icon 146 indicating the corresponding scalable progressive award value of \$5,000, and the MINI progressive prize icon 148 indicating the corresponding scalable progressive award value of \$1,000. The processor 38 then receives a player's selection of the selectable denomination icon 144 and renders the game denomination selection screen 150 on the game screen 142. In some embodiments, the game denomination selection screen 150 is displayed overlaying a portion of the virtual reels 70, 72, 74, 76, 78. The processor 38 then receives a player's selection of a player selectable game denomination icon 152 via the game denomination selection screen 150 indicating a selected game denomination value, determines a corresponding MDT denomination 140 associated with the selected game denomination value, determines the corresponding MINOR and MINI progressive award values associated with the selected game denomination value by multiplying the base MINOR and MINI progressive award values by the corresponding MDT denomination associated with the selected game denomination value, and animates the MINOR and MINI progressive prize icons 146, 148 to transform the current progressive award value to the corresponding progressive award value associated with the selected game denomination. In this example, the processor 38 receives a player's selection via the game denomination selection screen 150 indicating a selected game denomination value equal to \$0.10. The processor 38 then accesses the denomination data file 142 and determines the corresponding MDT denomination associated with the selected denomination value \$0.10 to be 1. The processor 38 then determines the corresponding MINOR progressive award value to be \$500 (i.e., base progressive award value×MDT denomination=corresponding progressive award value; \$500×1=\$500) and determines the corresponding MINI progressive award value to be \$100 (i.e., \$100×1=\$100). The processor 38 then animates the MINOR progressive prize icon 146 to transform the current MINOR progressive award value of \$5,000 to the corresponding MINOR progressive award value of \$500 associated with the selected game denomination value of \$0.10, and animates the MINI progressive prize icon 148 to transform the current MINI progressive award value of \$1,000 to the corresponding MINI progressive award value of \$100 associated with the selected game denomination value of \$0.10.

In method step 516, the processor 38 then initiates an instance of a computer-animated reel game 68 by animating the plurality of virtual reels 70, 72, 74, 76, 78 to simulate spinning the plurality of virtual reels and sequentially stopping the plurality of virtual reels 70, 72, 74, 76, 78 to display a game outcome using method 400.

Exemplary embodiments of a gaming device, a gaming system, and a method of providing an award to a player are described above in detail. The gaming device, system, and method are not limited to the specific embodiments described herein, but rather, components of the gaming device and/or system and/or steps of the method may be utilized independently and separately from other components and/or steps described herein. For example, the gaming device may also be used in combination with other gaming systems and methods, and is not limited to practice

with only the gaming device as described herein. Rather, an exemplary embodiment can be implemented and utilized in connection with many other gaming system applications.

A controller, computing device, or computer, such as described herein, includes at least one or more processors or processing units and a system memory. The controller typically also includes at least some form of computer readable media. By way of example and not limitation, computer readable media may include computer storage media and communication media. Computer storage media may include volatile and nonvolatile, removable and non-removable media implemented in any method or technology that enables storage of information, such as computer readable instructions, data structures, program modules, or other data. Communication media typically embody computer readable instructions, data structures, program modules, or other data in a modulated data signal such as a carrier wave or other transport mechanism and include any information delivery media. Those skilled in the art should be familiar with the modulated data signal, which has one or more of its characteristics set or changed in such a manner as to encode information in the signal. Combinations of any of the above are also included within the scope of computer readable media.

The order of execution or performance of the operations in the embodiments of the invention illustrated and described herein is not essential, unless otherwise specified. That is, the operations described herein may be performed in any order, unless otherwise specified, and embodiments of the invention may include additional or fewer operations than those disclosed herein. For example, it is contemplated that executing or performing a particular operation before, contemporaneously with, or after another operation is within the scope of aspects of the invention.

In some embodiments, a processor, as described herein, includes any programmable system including systems and microcontrollers, reduced instruction set circuits (RISC), application specific integrated circuits (ASIC), programmable logic circuits (PLC), and any other circuit or processor capable of executing the functions described herein. The above examples are exemplary only, and thus are not intended to limit in any way the definition and/or meaning of the term processor.

This written description uses examples to disclose the invention, including the best mode, and also to enable any person skilled in the art to practice the invention, including making and using any devices or systems and performing any incorporated methods. The patentable scope of the invention is defined by the claims, and may include other examples that occur to those skilled in the art. Other aspects and features of the present invention can be obtained from a study of the drawings, the disclosure, and the appended claims. The invention may be practiced otherwise than as specifically described within the scope of the appended claims. It should also be noted, that the steps and/or functions listed within the appended claims, notwithstanding the order of which steps and/or functions are listed therein, are not limited to any specific order of operation.

Although specific features of various embodiments of the invention may be shown in some drawings and not in others, this is for convenience only. In accordance with the principles of the invention, any feature of a drawing may be referenced and/or claimed in combination with any feature of any other drawing.

What is claimed is:

1. A gaming machine, comprising:
a cabinet;

a display device mounted to the cabinet; and a control unit operably coupled to the display device, the control unit including a processor programmed to execute an algorithm to render an animated sequence of computer-generated images on the display device including the steps of:

rendering a denomination configuration screen on the display device including a plurality of selectable denominations;

receiving an operator's selections of the selectable denominations and determining a Multi-denomination tokenization (MDT) multiplier based on an operator selected denomination;

determining an MDT denomination for each operator selected denomination based on the MDT multiplier; and

initiating a reel game by:

rendering a game screen on the display device including a plurality of virtual reels, a selectable denomination icon indicating a current game denomination value and a progressive prize icon indicating a current progressive award value associated with the current game denomination value;

receiving a player's selection of the selectable denomination icon and rendering a game denomination selection screen on the game screen including a plurality of player selectable game denomination icons associated with game denomination values corresponding to each operator selected denomination;

receiving a player's selection of a player selectable game denomination icon indicating a selected game denomination value;

determining a corresponding MDT denomination associated with the selected game denomination value;

determining a corresponding progressive award value associated with the selected game denomination value based on the corresponding MDT denomination and a base progressive award value; and

animating the progressive prize icon to transform the current progressive award value to the corresponding progressive award value associated with the selected game denomination.

2. The gaming machine of claim 1, wherein the processor is programmed to execute the algorithm including the steps of:

determining the MDT multiplier equal to an operator selected denomination having a lowest value of operator selected denominations.

3. The gaming machine of claim 1, wherein the processor is programmed to execute the algorithm including the steps of:

determining each MDT denomination by dividing a corresponding operator selected denomination by the MDT multiplier.

4. The gaming machine of claim 1, wherein the processor is programmed to execute the algorithm including the steps of:

determining the corresponding progressive award value associated with the selected game denomination value by multiplying the base progressive award value by the corresponding MDT denomination associated with the selected game denomination value.

5. The gaming machine of claim 1, wherein the processor is programmed to execute the algorithm including the steps of:

rendering the denomination configuration screen including a plurality of enabled denominations and a plurality

of disabled denominations, the plurality of enabled denominations being selectable by the operator and the plurality of disabled denominations not being selectable by the operator.

6. The gaming machine of claim 5, wherein the processor is programmed to execute the algorithm including the steps of:

receiving an MDT index value from the operator; and transforming a number of enabled denominations to disabled denominations based on the MDT index value.

7. The gaming machine of claim 6, wherein the processor is programmed to execute the algorithm including the steps of:

receiving the MDT index value from the operator indicating a desired lowest available denomination; and transforming current enabled denominations having corresponding denomination values lower than the desired lowest available denomination to disabled denominations.

8. A method of operating a gaming machine including a cabinet, a display device mounted to the cabinet, and a control unit including a processor operably coupled to the display device, the method including the processor performing an algorithm to render an animated sequence of computer-generated images on the display device including the steps of:

rendering a denomination configuration screen on the display device including a plurality of selectable denominations;

receiving an operator's selections of the selectable denominations and determining an MDT multiplier based on an operator selected denomination;

determining an MDT denomination for each operator selected denomination based on the MDT multiplier; and

initiating a reel game by:

rendering a game screen on the display device including a plurality of virtual reels, a selectable denomination icon indicating a current game denomination value and a progressive prize icon indicating a current progressive award value associated with the current game denomination value;

receiving a player's selection of the selectable denomination icon and rendering a game denomination selection screen on the game screen including a plurality of player selectable game denomination icons associated with game denomination values corresponding to each operator selected denomination;

receiving a player's selection of a player selectable game denomination icon indicating a selected game denomination value;

determining a corresponding MDT denomination associated with the selected game denomination value;

determining a corresponding progressive award value associated with the selected game denomination value based on the corresponding MDT denomination and a base progressive award value; and

animating the progressive prize icon to transform the current progressive award value to the corresponding progressive award value associated with the selected game denomination.

9. The method of claim 8, including the processor performing the algorithm steps of:

determining the MDT multiplier equal to an operator selected denomination having a lowest value of operator selected denominations.

27

10. The method of claim 8, including the processor performing the algorithm steps of:
 determining each MDT denomination by dividing a corresponding operator selected denomination by the MDT multiplier.
11. The method of claim 8, including the processor performing the algorithm steps of:
 determining the corresponding progressive award value associated with the selected game denomination value by multiplying the base progressive award value by the corresponding MDT denomination associated with the selected game denomination value.
12. The method of claim 8, including the processor performing the algorithm steps of:
 rendering the denomination configuration screen including a plurality of enabled denominations and a plurality of disabled denominations, the plurality of enabled denominations being selectable by the operator and the plurality of disabled denominations not being selectable by the operator.
13. The method of claim 12, including the processor performing the algorithm steps of:
 receiving an MDT index value from the operator; and transforming a number of enabled denominations to disabled denominations based on the MDT index value.
14. The method of claim 13, including the processor performing the algorithm steps of:
 receiving the MDT index value from the operator indicating a desired lowest available denomination; and transforming current enabled denominations having corresponding denomination values lower than the desired lowest available denomination to disabled denominations.
15. A non-transitory computer-readable storage media having computer-executable instructions embodied thereon to operate a gaming machine including a cabinet, a display device mounted to the cabinet, and a control unit including a processor operably coupled to the display device, when executed by the processor the computer-executable instructions cause the processor to perform an algorithm to render an animated sequence of computer-generated images on the display device including the steps of:
 rendering a denomination configuration screen on the display device including a plurality of selectable denominations;
 receiving an operator's selections of the selectable denominations and determining an MDT multiplier based on an operator selected denomination;
 determining an MDT denomination for each operator selected denomination based on the MDT multiplier; and
 initiating a reel game by:
 rendering a game screen on the display device including a plurality of virtual reels, a selectable denomination icon indicating a current game denomination value and a progressive prize icon indicating a current progressive award value associated with the current game denomination value;
 receiving a player's selection of the selectable denomination icon and rendering a game denomination selec-

- tion screen on the game screen including a plurality of player selectable game denomination icons associated with game denomination values corresponding to each operator selected denomination;
 5 receiving a player's selection of a player selectable game denomination icon indicating a selected game denomination value;
 determining a corresponding MDT denomination associated with the selected game denomination value;
 determining a corresponding progressive award value associated with the selected game denomination value based on the corresponding MDT denomination and a base progressive award value; and
 animating the progressive prize icon to transform the current progressive award value to the corresponding progressive award value associated with the selected game denomination.
16. The non-transitory computer-readable storage media of claim 15, wherein the computer-executable instructions cause the processor to perform the algorithm including the steps of:
 determining the MDT multiplier equal to an operator selected denomination having a lowest value of operator selected denominations.
17. The non-transitory computer-readable storage media of claim 15, wherein the computer-executable instructions cause the processor to perform the algorithm including the steps of:
 30 determining each MDT denomination by dividing a corresponding operator selected denomination by the MDT multiplier.
18. The non-transitory computer-readable storage media of claim 15, wherein the computer-executable instructions cause the processor to perform the algorithm including the steps of:
 determining the corresponding progressive award value associated with the selected game denomination value by multiplying the base progressive award value by the corresponding MDT denomination associated with the selected game denomination value.
19. The non-transitory computer-readable storage media of claim 15, wherein the computer-executable instructions cause the processor to perform the algorithm including the steps of:
 rendering the denomination configuration screen including a plurality of enabled denominations and a plurality of disabled denominations, the plurality of enabled denominations being selectable by the operator and the plurality of disabled denominations not being selectable by the operator.
20. The non-transitory computer-readable storage media of claim 19, wherein the computer-executable instructions cause the processor to perform the algorithm including the steps of:
 45 receiving an MDT index value from the operator; and transforming a number of enabled denominations to disabled denominations based on the MDT index value.
